UNITED STATES PATENT OFFICE

2,095,761

LIGHTING FIXTURE

Paul D. Phillips, Elmhurst, Ill., assignor to Benjamin Electric Mfg. Company, Des Plaines, Ill., a corporation of Illinois

Application May 25, 1935, Serial No. 23,364

2 Claims. (Cl. 240—11.3)

My invention relates to lighting fixtures. More particularly, it relates to a type of fixture for use in locations which require that the fixtures be dust-proof, such as flour or feed mills, grain elevators, starch and sugar mills, etc. A dust-laden atmosphere, such as is found in a flour or starch mill, is likely to be highly explosive and great care must be taken against its becoming ignited. In such an atmosphere, the dust is apt to settle on some rather flat surface of the fixture, forming a layer which may become heated to a temperature sufficient to cause ignition.

One of the objects of my invention is to provide a fixture which will minimize the danger of dust settling on the fixture and becoming ignited.

Further objects of the invention will be apparent from the description and claims.

In the drawing, the single figure shows a part 20 side-elevational, part sectional view of a fixture embodying my invention.

Referring to the drawing in detail, the construction shown comprises a hood 1, reflector means 2, a socket 3, and a lens 4, the hood, reflector means and the lens forming an enclosure for the lamp 5 supported in the socket, the socket being mounted on the hood in position to support the lamp extending downwardly therefrom into the enclosure, and the reflector means having an annular, outwardly and downwardly sloping portion 6 extending from the hood 1 and exposed to the heat from the lamp.

In testing fixtures of the general type shown in the drawing in dust-laden atmospheres, it was found that there were two bands or zones on the outside of the fixture which became hot enough to char grain dust piled on it during the test, these two zones being (1) the sloping sides of the lower portion of the hood casting, and (2) the generally flat portion of the main reflector member. A study of the temperature readings also disclosed that there was a circular zone at and near the outer rim of the glass lens which could be heated considerably more without reaching the danger point. In order to hold down the excessive temperature at the two danger zones indicated, and taking advantage of the possibility of increasing the temperature at and near the outer rim of the glass lens without reaching the danger point, an outer aluminum cover or shield 7 was added, which accomplishes the following purposes: (1) The under side of this shield, being of polished aluminum, forms a good heat reflector and turns back a large portion of the heat which reaches it from the

enameled steel reflector underneath; (2) since this spun aluminum shield fits tightly against the reflector at top and bottom, particularly in view of the asbestos gasket 18, a dead air space is provided between the shield 7 and the annular reflector portion 6, which acts as air insulation to prevent excessive temperature rise of the shield 7; (3) as the outer surface of the shield 7 is considerably more sloping than the annular reflector portion 6, it tends to lessen the amount 10 of dust settling on this part of the fixture, in effect giving a stream line design to the fixture.

Also, with a view to lessening the danger of dust explosions and also with a view to preventing waste of light, a plurality of inner reflectors 8 and 9 are provided adjacent the lamp which thus reflect light that would otherwise be lost up in the hood and also serve as baffles to prevent circulation of heated air up into the hood and to provide dead air spaces for heat insulation purposes and to reflect backward heat that would otherwise reach the lower portion of the aluminum hood and which might cause a dangerous rise of temperature. As shown by the lines indicating the direction of reflection, these reflectors are so designed that they reflect the light and heat down to a zone near the outer rim of the glass lens which, as indicated above, will not be heated to the danger point by additional heat and light reflection.

Any suitable materials may be used, the hood 1 being made of cast aluminum with a removable cast iron cap 10. The main reflector portion may be of porcelain enamel. The socket is held in place in the cap by means of screws 11 extending through the socket and threaded into the cap, and a suitable sealing gasket 12 is provided for the entrance of the feed wires.

The two annular reflector members 8 and 9 may be held in place by the hood by means of 40 outwardly extending flanges swedged over into an annular recess in the hood. The main reflector member is provided with a screw threaded neck 13 which is screwed into the lower threaded 45 portion of the hood. This screw threaded neck is provided with an inwardly extending flange 14 for forming with the gasket 15 one of the seals of the enclosure. When the main reflector member is removed by unscrewing it, the gasket 50 is still held in place by means of tongues 16 punched out from the lower annular reflector member 9 and engaging the gasket. The main reflector member may be secured in position by means of a set screw 17 threaded through the 55

hood and engaging the threaded neck 13 of the reflector.

If desired, additional heat insulating means may be provided in the form of the asbestos shield 18 conforming to the outer surface of the main reflector member. This shield 18 may also act as an air seal at the lower juncture of the shield 1 and reflector 2. The outer shield 1 may be of any suitable material, preferably thin sheet aluminum polished on the under side to reflect heat back into the enclosure. The lens may be secured in place in any suitable manner to provide a substantially dust-proof enclosure, as by means of a retaining ring 19 having an inwardly extending annular shoulder 20 and secured to the main reflector member by means of screws 21. Suitable gaskets 22 and 23 are provided, the upper one being shellacked in place to hold it in position when the lens is removed.

It will be seen that the construction shown provides a construction which will prevent dust from settling on that part of the reflector which is subjected to the greatest heat and that an air space is provided to afford heat insulation between the reflector member and the shield.

Further modifications will be apparent to those skilled in the art and it is desired therefore that the invention be limited only by the prior art and the scope of the appended claims.

Having thus described my invention, what I claim and desire to secure by Letters Patent is:

1. A light construction comprising a hood, reflector means, a socket and lens, said reflector means and lens forming an enclosure for the lamp supported in the socket, said socket being mounted on said hood in position to support a lamp extending downwardly therefrom into said enclosure, said reflector means having an annular

outwardly and downwardly sloping portion extending from said hood, the bulb of the lamp being spaced a substantial distance from the inner surface of the hood, said reflector means including an annular reflector member mounted in the hood and closely surrounding the neck of the bulb for reflecting the rays falling thereon toward a zone at or near the outer periphery of the lens, and a second annular reflector member mounted in the hood and closely surrounding a portion of the bulb below the neck portion for reflecting the rays falling thereon toward a zone at or near the outer periphery of the lens.

2. A dustproof fixture construction comprising a dustproof enclosure, a socket for supporting an electric lamp in said dustproof enclosure, and a shield for preventing dust from settling on a portion of said enclosure which is exposed to the heat from a lamp, said enclosure comprising a hood in which the socket is mounted, an inverted bowl-like reflector extending downwardly from said hood, and a lens adjacent the lower edge of the reflector, said shield being annular in form and lying above an annular portion of the reflector, said shield being spaced from said annular reflector portion throughout the greater portion of its extent and cooperating with said annular reflector portion to form a dust-tight enclosure, thus preventing access of dust to the hot annular reflector portion and providing a dead air insulating space between the hot reflector portion and the shield, all of the exposed portions of said shield having a greater slope than the portions of the reflector directly underneath, whereby less dust will settle on the fixture than would be the case if the shield were omitted.

PAUL D. PHILLIPS.
